UNITED STATES PATENT OFFICE.

JOHN L. KIMBELL, JR., OF SHREVEPORT, LOUISIANA, ASSIGNOR TO THE NATIONAL SOCIETY OF THE CHILDREN OF THE AMERICAN REVOLUTION, OF WASHINGTON, DISTRICT OF COLUMBIA, A CORPORATION OF THE DISTRICT OF COLUMBIA.

DESIGN FOR A HANDLE FOR SPOONS, FORKS, AND SIMILAR ARTICLES.

44,065.

Specification for Design.

Patented May 20, 1913.

Application filed April 9, 1913. Serial No. 760,043. Term of patent 14 years.

To all whom it may concern:

Be it known that I, JOHN L. KIMBELL, Jr., a citizen of the United States, residing at Shreveport, in the parish of Caddo and State of Louisiana, have invented a new, original, and ornamental Design for a Handle for Spoons, Forks, and Similar Articles, of which the following is a specification, reference being had to the accompanying drawing, forming part thereof.

The figure is a face view of a spoon, fork or similar article embodying my new design.

I claim—

The ornamental design for a handle for spoons, forks, and similar articles, as shown.

JOHN L. KIMBELL, JR.
